UNITED STATES PATENT OFFICE.

WESLEY C. JONES, OF PORTLAND, OREGON, ASSIGNOR OF ONE-HALF TO R. W. WOOD, OF PORTLAND, OREGON.

TATTING-SHUTTLE WINDER.

1,260,678.

Specification of Letters Patent. Patented Mar. 26, 1918.

Application filed July 27, 1916. Serial No. 111,641.

To all whom it may concern:

Be it known that I, WESLEY C. JONES, a citizen of the United States, residing in the city of Portland, county of Multnomah, 5 and State of Oregon, have invented certain new and useful Improvements in Tatting-Shuttle Winders, of which the following is a specification.

My invention relates to tatting shuttle 10 winders, and has among its salient objects to provide a simple and comparatively inexpensive tatting shuttle winder, capable of receiving any and all sizes and kinds of tatting shuttles, the principal object of my 15 invention, however, being to provide a shuttle winder on to which the shuttle can be easily and quickly placed, without the necessity of adjusting clips and without the necessity of springing one leaf, or side, 20 of the tatting shuttle, at its points, with the fingers, in order to attach it to the holder.

I am aware that a great many different 25 kinds of shuttle winders have been devised, but most of them require a specially constructed shuttle and those which do not require a specially constructed shuttle are so constructed that it is necessary to spring one side of the shuttle away from the other 30 side, at its points, with the fingers, in order to insert it in some holding means on the shuttle winder.

In my improved shuttle winder it is only 35 necessary to slip the shuttle on to the winder, and in so doing one of the sides of the shuttle, at its points, is automatically straightened, leaving the other, or outside 40 of the shuttle, at its points, spaced from the winder so that the thread can be easily and rapidly wound upon the shuttle as the 45 winder is turned by means of a small crank.

In order to more clearly explain my invention, I have illustrated the same in the accompanying sheet of drawings, which I 50 will now describe.

Figure 1 is a front elevation of my invention with a shuttle applied thereto.

Fig. 2 is an edge view thereof; and

Fig. 3 is an end view showing the shuttle 55 in the position of being started on to the holder.

Referring now more in detail to the drawings, my invention comprises a body member 1, consisting of a strip of material, substantially as shown, having at its opposite

ends two fingers 2 and 3, formed integrally therewith and overlapping the body 1, crosswise thereof, as shown, with their free ends bent toward the plane of the body, as shown. The body 1, is also provided in its 60 middle portion with a bearing piece 4, formed thereon. Secured to the body 1, as at 5, is a crank 6, extended through the upper end of a handle 7. A thread guide 8, is inserted in the handle, as clearly shown, 65 through which the thread is guided on to the shuttle, designated S.

In order to apply the shuttle to the handle, it is only necessary to place the shuttle in the position shown in Fig. 3, so that the 70 ends of the fingers 2 and 3, pass between the sides of the shuttle at their ends, and then move the shuttle on to the holder in the direction indicated by the arrow, Fig. 3. It will be noticed that the middle portion 75 of the inner side of the shuttle slides up on to the bearing member 4, while the ends of the inner side of the shuttle pass underneath the fingers 2 and 3, as clearly illustrated in Fig. 2. This movement of 80 the shuttle on to the holder straightens the side of the shuttle attached to the body, or winder, leaving an open space between the fingers 2 and 3, and the opposite ends of the outer side of the shuttle so that the 85 thread T, to be wound upon the shuttle, can pass therebetween. Attention is also called to the fact that the curved front and back of the fingers operate to guide the thread between the opposite ends of the outer side 90 of the shuttle and the fingers, so that the winder can be turned rapidly without danger of the thread catching either on the fingers or on the ends of the shuttle.

I prefer to make my invention of sheet 95 metal in order that it may be rapidly and cheaply stamped therefrom, but I am aware that changes can be made therein without departing from the spirit thereof, and I do not, therefore, limit the invention to the 100 form here shown, except as I may be limited by the hereto appended claims.

I claim:

1. A tatting shuttle winder comprising a body revolvably mounted and having two 105 projecting fingers adapted to be inserted between the sides of the shuttle, near its points, before and as the shuttle is placed upon the revolvable body, said body having a middle portion adapted to bear against 110

the middle portion of the shuttle as it is moved on to said finger.

2. A tatting shuttle winder comprising a body provided at its ends with two fingers 5 bent crosswise over the body at its ends, at a space therefrom, and having a middle bearing portion on the same side between said fingers, whereby as a shuttle is placed upon said body said fingers first pass between the sides of the shuttle near its ends, 10 before said shuttle passes on to said middle bearing portion, substantially as shown and described.

3. A tatting shuttle winder of the character shown and described comprising a handle, a long body revolvably mounted thereupon with means for turning the same, said 15

body being provided at its ends with curved laterally projecting fingers adapted to be first inserted laterally between the sides of 20 a shuttle, near its points, and having a middle bearing portion adapted to engage the outside of a shuttle in the middle, whereby to flex one side of the shuttle away from the other side, and a thread guide in alignment 25 with the outer side of said fingers for guiding the thread on to said shuttle as said body is turned, substantially as described.

Signed at Portland, Multnomah county, Oregon, this 3rd day of July, 1916.

WESLEY C. JONES.

In presence of—

I. M. GRIFFIN,
G. L. LITZENBERG.
